US00D900783S

(12) **United States Design Patent** (10) **Patent No.:** **US D900,783 S**
(45) **Date of Patent:** **** Nov. 3, 2020**

(54) **HEADBAND PORTION OF HEADPHONE DEVICE**

(71) Applicant: **New Audio LLC**, New York, NY (US)

(72) Inventor: **Jonathan E. Levine**, New York, NY (US)

(73) Assignee: **New Audio, LLC**, New York, NY (US)

(**) Term: **15 Years**

(21) Appl. No.: **29/689,386**

(22) Filed: **Apr. 29, 2019**

Related U.S. Application Data

(63) Continuation of application No. 29/628,837, filed on Dec. 7, 2017, now Pat. No. Des. 852,166, which is a continuation of application No. 29/571,804, filed on Jul. 21, 2016, now Pat. No. Des. 805,056, which is a continuation of application No. 29/520,926, filed on Mar. 18, 2015, now Pat. No. Des. 762,190, which is a continuation of application No. 29/481,787, filed on Feb. 10, 2014, now Pat. No. Des. 727,280.

CLAIM

The ornamental design for a headband portion of a headphone device, as shown and described.

DESCRIPTION

FIG. 1 is a perspective view of a headband portion of a headphone device showing my new design, as viewed from the top and front.

FIG. 2 is a front profile view of the headband portion shown in FIG. 1.

FIG. 3 is a back profile view of the headband portion shown in FIG. 1.

FIG. 4 is a first side profile view of the headband portion shown in FIG. 1.

FIG. 5 is a second side profile view of the headband portion shown in FIG. 1.

FIG. 6 is a plan view of the headband portion shown in FIG. 1; and,

FIG. 7 is an inverse plan view of the headband portion shown in FIG. 1.

The details shown in broken lines illustrate features that are for illustrative purposes only; the broken lines form no part of the claimed design.

1 Claim, 5 Drawing Sheets
